UNITED STATES PATENT OFFICE.

JOHN A. LANCASTER, OF JERSEY CITY, NEW JERSEY.

TYPEWRITER SHEET.

Application filed October 23, 1920. Serial No. 418,950.

To all whom it may concern:

Be it known that I, JOHN A. LANCASTER, a citizen of the United States, residing in Jersey City, in the county of Hudson, State 5 of New Jersey, have invented certain new and useful Improvements in Typewriter Sheets, of which the following is a specification.

The invention relates to sheets written 10 upon in writing machines and more particularly to the sheets of paper written or printed upon in typewriting machines.

In the operation of a common form of writing machine, the typewriter, the sheet of 15 material, as paper, to be written upon is moved about the platen. The portion of the sheet immediately following that being written upon, including also in the case of the so-called "blind" typewriter the part 20 of the sheet actually being written upon, is concealed by the platen from the view of the operator. As the last or end portion of the sheet is thus hidden, the operator is unable 25 properly to gage the work, as for utilizing to the fullest extent the remaining space or for leaving the usually desired margin, and is therefore liable to overwrite the sheet, that is to say, carry the writing beyond the 30 desired or proper limits.

Various instrumentalities have been provided to warn the operator of the approach 35 of the end of the sheet, such instrumentalities taking the form of mechanical devices to be attached to the typewriter or to the sheet itself. But such devices are objectionable on various grounds, as for reasons of economy, simplicity of construction, or convenience of operation.

With the foregoing defects in mind, therefore, 40 objects of the invention are to provide means for warning the operator of the approach of the end of the sheet, which means shall be economical, of extreme simplicity, and unfailing in operation.

The invention consists in providing a 45 sheet of material, as paper, for use in a writing machine, as a typewriter, which sheet shall contain in itself the means for warning the operator of the approach of the end of the sheet.

In one form of the invention, a sheet of 50 typewriter paper is provided which has a water-mark suitably disposed therein which acts as such signal or warning means.

In another form of the invention, a sheet 55 of writing material is provided which has

side marginal lines, such lines being broken at a suitable place to furnish the desired signal or warning to the operator.

These and other forms of the invention 60 will be more fully set forth in the following description.

In the drawings which are referred to herein and made part hereof are illustrated several embodiments of the invention, the 65 same serving to illustrate the invention and make clear the principles thereof.

Of the drawings:

Fig. 1 is a plan of a sheet of typewriter paper having a water-mark therein to act 70 as a signal for the purpose described;

Fig. 2 is a similar view with a water-mark of different design;

Fig. 3 is a similar view of a sheet having broken side marginal lines, the break acting 75 as the signal; and

Fig. 4 is a similar view in which a water-mark is shown near the top and bottom of the sheet, respectively.

Referring now in detail to the invention, 80 there is illustrated in Fig. 1 of the drawings one embodiment of the invention, the same comprising a sheet of paper having at a suitable distance from the bottom or end thereof a physical peculiarity sufficiently 85 striking to catch the eye of the operator and thereby act as a signal to the operator that the end of the sheet is approaching, the operator thereby being enabled to conform 90 the work accordingly.

As shown, this physical peculiarity consists of a water-mark 7 in the paper extending horizontally across the sheet a substantial distance and being of a suitable width.

It will be noted that the water-mark may 95 be of any suitable design or dimensions, the mark in Fig. 2, for example, showing the word "End," the intent of the same being readily apparent. These letters may be of any suitable size and design and spaced 100 apart as desired. It will be further observed that the mark may be of various other natures, if desired, to indicate various things.

In using sheets of paper with entirely 105 blank surfaces and which sheets may be used with either end serving indifferently as the top or bottom, each end may be provided with the warning water-mark, made in the paper at a suitable distance therefrom, as 110 shown in Fig. 4, thus obviating any possible confusion in the use of the paper. When the

signal mark is thus used at both ends, the mark at the top may serve as a top marginal guide if it be desired to bind the sheet at the top.

5 A modification of the invention is shown in Fig. 3, in which is illustrated a sheet of paper having side marginal lines, said sheet being in common use. In the case of this sheet the marginal lines may be broken or 10 interrupted at a suitable distance from the bottom of the sheet and to a suitable extent, the break 9 in the lines serving as the desired signal mark or warning to the operator. Preferably and as shown, the marginal lines 15 at both sides of the sheet are thus broken, thus making a signal at each side of the sheet to attract the attention of the operator.

It will be seen that a sheet of typewriter paper fashioned according to the principles 20 of the invention as hereinbefore set forth will carry out the objects of the invention as enumerated and also possesses other advantages, as, to indicate the ownership or origin 25 of the sheet, or to serve advertising purposes.

25 The invention in its broader aspects is not limited to the precise embodiments set forth and described as many changes may be made in the details without departing from the spirit of the invention or sacrificing any of 30 its chief advantages.

I claim:

1. A sheet of paper for use in a writing machine, having near one end an isolated discernible physical peculiarity to indicate 35 the approach of the end of the sheet when the sheet is being written upon, said physical peculiarity being spaced at a definite predetermined position from the end of the sheet

so that the operator may be enabled, when discerning the physical peculiarity, properly to gage the work and thereby avoid overwriting the sheet. 40

2. A sheet for use in a writing machine, having near one end an isolated mark to indicate the approach of the end of the sheet 45 when the sheet is being written upon, said mark being spaced at a definite predetermined position from the end of the sheet, so that the operator may be enabled, when discerning the mark, properly to gage the work 50 and thereby avoid overwriting the sheet.

3. A sheet of paper for use in a writing machine, having near one end an isolated water-mark to indicate the approach of the end of the sheet when the sheet is being written upon, said mark being spaced at a definite predetermined position from the end of the sheet, so that the operator may be enabled, when discerning the mark, properly to gage the work and thereby avoid overwriting the sheet. 55

4. A sheet of paper for use in a writing machine, having near each end an isolated mark to indicate the approach of the end of the sheet when the sheet is being written 65 upon in either of its reversed positions, each of said marks being spaced at a definite predetermined position from the end of the sheet, so that the operator may be enabled, when discerning the mark, properly to gage the work and thereby avoid overwriting the sheet. 70

In testimony whereof, I have signed my name to this specification.

JOHN A. LANCASTER.
